7 Claims. (Cl. 198—21)

The present invention relates to a novel apparatus adapted to facilitate the separation of cut boards from vertically stacked cants or boards requiring further processing.

This invention is concerned with the separation of cut boards after being formed in a lumber processing mill. The modern mill operation often includes a horizontal resaw through which are fed the squared off cants or slabs which are to be cut into usable dimension lumber. Such a horizontal resaw normally produces a cut board upon which is stacked the remainder of the cant or another board which may require future processing. Normally such cut boards must be separated by manual procedures which are both time consuming and expensive. For this reason the present invention contemplates a mechanical device which will automatically separate the usable board from the remainder of the cant which must be further processed.

It is a first object of this invention to provide a lumber separator which is capable of handling the output of a high speed horizontal resaw assembly. In order to accomplish this purpose the present invention utilizes both transverse and longitudinal movement of the board which is to be separated from the remaining portion of the cant.

It is another object of this invention to provide a lumber separator in which the movement of the boards themselves is utilized to effect the necessary separation. This is accomplished by providing a fixed abutment against which the moving board assembly must collide, thereby causing a portion of the assembly to stop, while allowing the remainder of the assembly to pass over the abutment. Thus no additional mechanical linkages, pusher bars or other apparatus are necessary to complete the desired separation of board and cant.

It is another object of this invention to provide suitable controls which are capable of activating the conveyor assemblies to complete the separation steps. These controls are activated by electrical components and are positioned so as to be actuated by the boards themselves at the proper time to maintain the necessary sequence of events leading to the final separation.

Another object of this invention is to provide controls and movable bulkheads so as to allow a manual operator to alternately prevent separation of the assembly when such separation is unnecessary. These controls will be utilized at the final working of a cant, should the last board be an even thickness so as to produce two boards with the final sawing operation.

Another object of this invention is to provide movable cant controls so that the remaining cant or boards may alternately be directed back to the horizontal resaw operation, or may be directed to a chipper or other waste processing machine.

These and further objects will be evident from a study of the following disclosure taken in conjunction with the accompanying drawings to which references will be made. The embodiment illustrated in the drawings is illustrative only and is not intended to limit or restrict the scope of the invention which is properly defined in the annexed claims.

In the drawings:

FIGURE 1 is a top view of the separator with the delivery conveyor and the return conveyors broken away at the left hand side, the central portion of the separator

2

being broken away and the final conveyor table being broken away at the right side of the figure;

FIGURE 2 is a side view of the assembly as seen in FIGURE 1;

5 FIGURE 3 is a sectional view taken along line 3—3 in FIGURE 1;

FIGURE 4 is an enlarged sectional view taken along line 4—4 in FIGURE 1, with the transverse conveyor shown in its lowered position;

FIGURE 5 is a view similar to FIGURE 4, but taken along line 5—5 in FIGURE 1, showing the conveyor in its raised position;

FIGURE 6 is taken along the same plane as FIGURE 5, but extends farther to the left and illustrates the separation of board and cant;

FIGURE 7 is an enlarged section view taken through line 7—7 in FIGURE 5;

FIGURE 8 is a sectional view of a portion of the side rail as seen along line 8—8 in FIGURE 4;

FIGURE 9 is an enlarged sectional view taken along line 9—9 in FIGURE 8; and

FIGURE 10 is a circuit diagram of the electrical controls for a single separator assembly.

Modern lumber processing often includes a horizontal resaw mill in which squared off cants or slabs are cut horizontally into the desired rough boards of proper thickness. The horizontal resaw is basically a large band saw with a horizontal cutting flight of saw teeth. The boards being cut are moved along a conveyor past the stationary saw. The product therefore is a cut board upon which is stacked the remainder of the cant, or in the case of the final cut, a narrow strip of board or possibly a second board of a desired thickness. The separation of the lower board from the remainder of the cant presents a problem since this board should be directed further to a planing mill edger or a drying kiln, and the remainder of the cant must be directed back to the horizontal resaw for further cutting operations. The apparatus to be described below presents an automatic device for effecting this separation.

The separator is generally shown in FIGURES 1, 2 and 3. It consists of a fixed framework 10 which shall include all the fixed supporting members for the various conveyors which will be described. The first element on the framework 10 is a delivery conveyor 11. The conveyor 11 comprises outfeed rollers 12 which may be power driven by any suitable means (not shown). The outfeed rollers 12 of the delivery conveyor 11 carry the boards past the horizontal resaw during the cutting operation. That portion of the delivery conveyor illustrated in FIGURES 1-3 is the delivery end thereof. The boards 9, shown in FIGURE 1, are moving in the direction of arrows 9a.

55 The apparatus illustrated in the drawings is designed to service a pair of lumber lines emanating from a horizontal resaw assembly. Thus the apparatus includes two duplicate devices which are mirror images of one another and which operate in precisely the same manner. A divider 19 separates the two devices along the center line 60 of table 13. Thus two boards 9 are illustrated at the left hand side of the figure and will be processed entirely independently of one another. For purposes of description only a single device will be referred to, although it must be kept in mind that identical numbers will distinguish identical corresponding parts of both devices. The two separators may obviously be used as shown in FIGURE 1, or may be divided so as to eliminate one device where a single lumber line is being processed.

65 The second basic element in the separator is a receiving table 13. The table 13 is supported basically between a pair of longitudinal side channels 14 which constitute a fixed part of the framework 10. Intermediate

longitudinal channels 14a are also provided for foundation purposes. The channels 14 and 14a support cross channels 15 which interlock between the two separating devices. The cross channels 15 along each device constitute a pair of outwardly facing channels having a space between their vertical webs. Mounted on the framework 10 are upper plates 17 which constitute the supporting elements of the receiving table 13. The plates 17 are rigidly fixed to the framework 10 by means of supporting brackets 18. It is to be noticed from FIGURE 3 that the right hand end of each plate 17 is elevated above its left hand end. This slight rippling effect along the table 13 is designed to protect the lateral conveyors 20 which are located within the spaces bounded by the outwardly facing channels 15. Thus as boards 9 are pushed onto the receiving table 13 by the action of rollers 12, the leading ends of the boards 9 will strike the upper surfaces of the plates 17 and will bound across the open areas in which are located the cross channels 15.

Up to this point it may be understood that the boards 9 are fed from the roller 12 onto the plates 17. It is important to note that the rollers 12 are elevated slightly above the upper surfaces of plates 17 so that the rear end of each board 9 remains in an elevated position and bridges slightly over the left hand end of the receiving table 13. By this action the boards 9 will be pushed along the receiving table 13 until the boards 9 rest entirely on the plates 17.

Directly below the paths of the boards 9 are a plurality of lateral conveyors 20. Each conveyor 20 is directed perpendicularly to the position of the boards 9 on the plates 17. Each lateral conveyor is identical in structure and can best be seen in the enlarged illustrations of FIGURES 4 through 7. The conveyor includes an inboard idler sprocket 21 and an outboard sprocket 22. The outboard sprocket 22 is adapted to be driven through a common shaft 19. The two sprockets 21 and 22 are enmeshed with a chain 23 which is loosely wrapped about them to form a continuous loop. The chain 23 is a common sprocket chain and has smooth links which are capable of supporting articles placed thereon.

The chain 23 has an upper flight which extends across the paths of the moving boards 9. This upper flight is mounted within a chain support frame 24. The support frame 24 is basically an upwardly facing channel along which the chain is slidably carried. The support frame 24 is vertically movable and is mounted on the framework 10 by means of an idler link 25 and a bell crank 26 which cooperate to form a parallelogram support linkage. The bell crank 26 is adapted to be moved from the position shown in FIGURE 4 to the position illustrated in FIGURE 5, by means of a movable cylinder assembly 28. The bell crank 26 of the various aligned conveyors 20 is operated by means of a common operating shaft 26a.

At the outboard end of each lateral conveyor 20 and adjacent the sprockets 22 is a longitudinal abutment 30 which is the vertical web of the side channel 14. This abutment 30 is placed along the outboard ends of the conveyors 20 and is mounted adjacent a row of rollers 31. The rollers 31 constitute a conveyor assembly along which the lower board is carried parallel to the length of the moving boards 9 being delivered by the delivery conveyor 11.

The basic operation of these elements is quite simple. The supporting frame 24, below each chain 23, is moved in unison with each of the other aligned chains 23 by means of the cylinder assembly 28. Each chain 23 is movable from a first position illustrated in FIGURE 4, wherein the top chain surface is slightly below the upper surface of the adjacent plate 17, to a second position illustrated in FIGURE 5, wherein the top surface of the chain 23 is slightly above the adjacent upper surface of the plate 17. Thus the chain 23 in each lateral conveyor 20, can alternately clear the moving boards 9 as they are

received on the table 13, or lift the boards 9 from the plates 17. The outboard sprockets 22 are rotated in the direction of the arrow illustrated in FIGURE 5. Thus after a board has been fully received on the table 13, it may be lifted by means of the cylinder assembly 28 and frame 24 so that the boards 9 rest only on the moving chains 23. The chains 23 thus carry the boards 9 laterally, as seen in FIGURE 5. The laterally moving boards are then deposited on the rollers 31 and will continue to slide until the lower board strikes the raised abutment 30. The speed of the chains 23 is very rapid and results in a high momentum of the moving boards 9 as they strike the abutment 30. The tangential upper surfaces of the rollers 31 is located intermediate the two positions of the top surfaces of the chains 23, supported by frames 24. The elevation of the abutment 30 above the second position of the chain 23 is less than the thickness of the lower board 9, which is to be separated from the remaining cant. Thus the remainder of the cant will fly over the raised abutment 30 and the cut board 9 will remain on the rollers 31. The rollers 31 may be driven by any common drive mechanism so as to propel the separated boards 9 parallel to the abutment 30.

The disposal of the cants 9 requires two separate procedures. During the initial cutting of the cant 9 the remainder of the can should be directed back to the resaw operation for further cutting. In order to effect such motion, a movable gate 32 is provided adjacent each side channel 14. The gate 32 is normally inclined in the position illustrated in full line in FIGURE 6 and shown in FIGURES 1 and 2. The dump gate 32 is pivotally mounted at its lower end as shown at 32a in FIGURE 6. This pivotal mounting 32a is a direct connection to the basic framework 10. Directly to the left of the gate 32, as seen in FIGURE 6, is a return conveyor 33. The return conveyor 33 is a conventionally powered roller conveyor which will effect motion of the cant in a direction opposite to the motion of the boards 9 as they are delivered from the delivery conveyor 11. Within the space between the return conveyor 33 and the vertical frame member 57 is a waste conveyor 34. The conveyor 34 is normally covered by the gate 32 so that the slabs will ride from the inclined gate 32 and be deposited on the return conveyor 33. The waste conveyor 34 is properly connected to a conveyor system leading to a chipper apparatus or other waste disposal means. Where a cant has been sawed to a point where the remainder of the cant is unusable, this remainder will be deposited on the waste conveyor by rotation of the conveyor gate 32 to the dashed line position illustrated in FIGURE 6. Thus cants riding over the abutment will fall between the gate 32 and the vertical post 57 and be directly deposited on the waste conveyor 34.

In normal sawing operation, it is also possible to complete the sawing of the cant with two boards of the desired thickness being one on top of the other. In other words, the sawing operation results in the even cutting of the desired boards. When this occurs, both boards should be directed along the rollers 31 adjacent to the raised abutment 30. In order to effect this action the mechanism illustrated in FIGURES 8 and 9 has been included in the present apparatus. This mechanism includes movable stop arms 35 which are pivotally mounted along the abutment 30. The normal position of stop arms 35 is flush with the surfaces of the side channels 14. Each arm constitutes a bell crank which is pivoted at 36. The arms 35 are movable to an upraised position illustrated in dashed lines in FIGURE 8, where the arms 35 will block movement of the upper board over the abutment 30. The arms 35 are adapted to be actuated by means of a common connecting linkage 37.

Both the gate 32 and the arms 35 are actuated by suitable cylinder assemblies. The gate 32 is adapted to be moved upwardly by a double acting cylinder assembly 29. Assembly 29 rests at the position illustrated in FIG-

URE 6. The arms 35 are adapted to be moved to the upper position illustrated in dashed lines in FIGURE 8 through the connecting linkage 37 by means of a common double acting cylinder assembly 38. The cylinder assembly 38 rests in the full line position illustrated in FIGURE 8.

The basic object of this invention is to provide a completely automatic separating assembly which is subject to manual alternate controls. In order to provide a machine which is automatic in operation the boards 9 must themselves control the raising and lowering of the chains 23. This is accomplished first by means of a hinged plate 40 at the end of the receiving table 13 adjacent the delivery conveyor 11. Each hinged plate 40 lies directly below the paths of the boards 9 as they are fed from the delivery conveyor 11. Each plate 40 is independently mounted on a framework 10 by means of a hinge 41. A limit switch 42 is provided below each plate 40 and biases the end of the plate 40 opposite to the hinge 41 to a position slightly elevated above the upper surfaces of the plates 17. Due to the elevation of the roller 12 above the plates 17, the hinged plate 40 below each board will not be engaged by the moving board until the rear end of the board has cleared the last roller 12. At this time the board will fall upon the plate 40, causing the plate to pivot downwardly and thereby actuate the switch 42. The second control along the receiving table 13 is a simple limit switch 43 which is mounted between the supporting portions of the side rollers 31. The switch 43 is mounted on the framework 10 and is adapted to be contacted by the leading edge of the moving boards 9 as they are carried along the chains 23.

The operation of these switches from a mechanical standpoint is believed to be clear from this description. The circuit in which the switches is utilized is illustrated in FIGURE 10. Besides the switches 42 and 43, there is also provided a manual switch 44 adapted to control the movable gate 32, and a second manual switch 45 adapted to control the arms 35. The switch 42 is normally open, while the switch 43 is normally closed. Both manual switches 44 and 45 are normally open and are preferably of the push button type which is momentarily closed by contact of a person's finger.

Power for the control circuit is provided by two lines 46 and 47 which are wired to a suitable power source (not shown). The circuit for control of the chains 23 is a direct series connection of switches 42 and 43 with a solenoid 55 which, when actuated, operates a valve to supply pressure to the cylinder assembly 28 to thereby raise the chain support frames 24. Thus, when a board contacts the switch 42, the circuit to solenoid 55 is completed, and the chains 23 are raised to the position illustrated in FIGURE 5, to thereby carry the boards 9 across the receiving table 13. When the boards have been carried into contact with the limit switch 43, the circuit to the solenoid 55 will be opened and the pressure to cylinder assembly 28 will be reversed to thereby return it to its initial position.

The remainder of the circuitry illustrated in FIGURE 10 is provided to automatically operate the gate 32 and arms 35 at the proper times when such operation is desired. In order to effect such operation, the operator of the machine must merely close the respective switch 44 or 45 at some time during the cycle. Each switch 44 and 45 is wired in a parallel circuit, as can be seen in FIGURE 10. The first switch 44, which operates the gate 32, is wired in series across the lines 46 and 47 with a relay 48 and contacts 51a of a time delay relay 51. The relay 48 is provided with three sets of contacts 48a, 48b and 48c. The first set of contacts 48a are wired across the terminals of the switch 44 and hold the relay 48 in its activated relationship after closing of the switch 44. The second set of contacts 48b are wired in series with a solenoid 50 which, when activated, operates a valve to direct pressure to the cylinder assembly 29 to thereby

move the gate 32 to the position shown in dashed lines in FIGURE 6. The third contacts 48c are connected to the line 46. The manual switch 45 is wired in a similar circuit shown in FIGURE 10. Switch 45 is wired in series with a relay 52 and the contacts 51a across the lines 46 and 47. Relay 52 is also provided with three sets of contacts 52a, 52b and 52c. The first set of contacts 52a is wired across the terminals of the switch 45 and operates to hold the relay 52 in its activated condition. The second set of contacts 52b is wired in series with a solenoid 53 which operates a valve to direct pressure to the cylinder assembly 38 to thereby move the arms 35 to their raised positions illustrated in dashed lines in FIGURE 8. The third set of contacts 52c is connected to the line 46 and are wired in parallel with the contacts 48c. As may be seen in FIGURE 10, both relays 48 and 52 are provided with parallel contacts 48b and 52b and 48c and 52c. These parallel contacts are connected respectively to lines 58 and 59.

Wired in parallel with the solenoid 55 is a relay 54. Relay 54 is therefore connected in series with the switches 42 and 43 across the lines 46 and 47. The relay 54 is provided with two sets of contacts 54a and 54b. A final relay 56 is also provided in the circuit and is provided with two sets of contacts 56a and 56b. Relay 56 is wired across line 47 by a line 61 and is connected at its remaining terminal to the first set of contacts 54a. The contacts 54a are also connected to the line 58 which is connected through contacts 48c or 52c to the line 46. Thus closing of either set of contacts 48c or 52c will result in the activation of relay 56 when the relay 54 has been actuated. The line 58 is also connected directly to the first set of contacts points 56a which are also wired to a line 60, connected to the time delay relay 51. The remaining terminal of time delay relay 51 is directly connected to the power line 47. Thus the first set of contacts 56a act as holding points to complete the circuit of relay 51 regardless of the condition of relay 54 after initial actuation thereof. The second set of contacts 54b are holding contacts and are connected across the terminals of switch 42 to maintain the relay 54 in its activated condition after initial closing of the switch 42. The final contacts 56b are connected between the power line 46 and the line 59 which leads to the contacts 48b and 52b.

The operation of this circuit is very simple. Assuming that a cant has been cut with the remainder which is desired to be resawed, neither manual switch 44 or 45 will be operated. As the board falls on the receiving table 13, it will strike the plate 40 and thereby close the switch 42. This closure will result in actuation of the solenoid 55 and cause the chains 23 to be lifted to thereby carry the board 9 to the abutment 30. When the board edge strikes the limit switch 43, the circuit to the solenoid 55 will be broken and the cylinder assembly 28 will return the chains 23 to their first positions. The lower board will then strike the abutment 30 and the cant will ride over the abutment 30 and be deposited by the gate 32 on the return conveyor 33. No other operation will result. The solenoid 55 will be held in its operational position during lateral movement of boards 9 by the closing of the holding contact points 54b. The closing of the contact points 54a will be ineffectual, since they alone will not complete a power circuit.

Assuming first that the cant has been cut to a condition wherein the remaining portion of the cant is unusable, it is desirable that the gate 32 be raised to the dashed line position illustrated in FIGURE 6. This is accomplished by closing the switch 44 during the time in which the boards 9 are being deposited on the table 13 by the delivery conveyor 11. Closing of switch 44 results in the actuation of relay 48 and closes the three sets of contacts 48a, 48b and 48c. The circuit is held in a complete condition by the holding contacts 48a. After the boards have been deposited on the receiving table 13 and the rear

ends thereof have struck the plate 40, the switch 42 will be closed as before. The lateral movement of the board will proceed as described in the preceding paragraph, but closing of the relay contacts 54a will now result in the completion of the circuit to the relay 56. Thus the contacts 56a will insure the completion of a circuit to the time delay relay 51 and at the same time, the contacts 56a will complete a power circuit to the solenoid 50 through the line 59 and contact points 48b. Thus the gate 32 will be raised to the dashed line position illustrated in FIGURE 6, while the boards 9 are being carried toward the abutment 30. When the edge of the board strikes the limit switch 43, the circuit to the solenoid 55 and relay 54 will be opened and the chains 23 will be lowered as before. However, the circuit to relay 56 will remain in a complete condition due to the action of the holding contacts 56a which by-pass the contacts 54a. Thus the gate 32 will remain in its upper position due to the continuance of power to the solenoid 50. This circuit will remain completed until the time delay relay 51 opens the contacts 51a. The relay 51 is a conventional component and may be adjusted to hold the circuit closed as long as desired. The opening of contact points 51a results in the activation of relay 48 and the opening of all of the circuits so as to preset the circuits for the next board.

Should the final cut of the cant produce a split of two boards of identical desired thickness, the arms 35 should be raised to the position illustrated in dashed lines in FIGURE 8. This is accomplished in precisely the same manner as is the raising of the gate 32. Since the circuitry for the solenoid 53 is identical to that associated with the solenoid 50, no further description of its operation will be given.

Thus there is provided a completely automatic control circuit for the mechanical separating mechanism described above. Obviously various changes could be made in both the mechanical and electrical components without deviating from the intended scope of this invention. For this reason the use of a double separating assembly is illustrated only as an example. The assembly may be made as long as necessary to accommodate the boards being cut by the resaw assembly. The addition of units along the receiving table 13 should be obvious.

Whether the cylinder assemblies are hydraulically operated or pneumatically operated is a matter of design choice. In most installations the conveyor forms and directions will be varied from that shown due to local conditions.

Equivalent changes are possible without changing the invention and therefore the invention itself is to be limited only by the following claims.

Having thus described our invention, we claim:

1. A device for separating vertically stacked boards, comprising:
  - a fixed framework;
  - a delivery conveyor mounted on said framework adapted to convey vertically stacked boards;
  - a receiving table located on said framework adjacent the delivery end of said conveyor having an upper surface adapted to support boards deposited thereon by said delivery conveyor;
  - a plurality of lateral conveyors mounted on said framework perpendicular to the length of the boards deposited on said receiving table, said lateral conveyors being conjointly mounted on said framework for movement between a first position wherein the top surfaces of said lateral conveyors are located below the upper surface of said receiving table to a second position wherein the top surfaces of said lateral conveyors are located above the upper surface of said receiving table;
  - a fixed abutment mounted on said framework adjacent one aligned end of each of said lateral conveyors toward which the top surfaces thereof are directed

and parallel to the lengthwise position of the boards deposited on said receiving table, the top edge of said abutment being located above the top surfaces of said lateral conveyors when in said second position at a height less than the thickness of the lower board being separated;

means drivingly connected to said lateral conveyors adapted to propel vertically stacked boards supported on said lateral conveyors against said abutment with force sufficient to cause boards resting on the lowermost board of each stack to slide therefrom over said abutment;

and longitudinally directed conveyor means mounted on said framework intermediate said lateral conveyors and directed perpendicularly thereto, the elevation of the top surface of said conveyor means being intermediate the elevations of the top surfaces of said lateral conveyors at said first and second positions.

2. A device as defined in claim 1, further comprising: actuating means mounted on said framework operatively connected to said transverse conveyors adapted to selectively effect movement of said transverse conveyors between said first and second positions;

first means located on said framework at the end of said receiving table adjacent said delivery framework operatively connected to said actuating means adapted, when activated, to cause said actuating means to move said transverse conveyors from said first position to said second position, said first means being engageable with boards on said delivery table so as to be activated when the rear ends of the boards are deposited on said table by said delivery conveyor;

and second means located on said framework adjacent said abutment operatively connected to said actuating means adapted, when activated, to cause said actuating means to move said transverse conveyors from said second position to said first position, said second means being engageable with boards on said transverse conveyors so as to be activated when the boards have traversed the lengths of said transverse conveyors.

3. A device as defined in claim 1 wherein each of said lateral conveyors comprises:

an inboard idler sprocket rotatably mounted on said framework about a first common longitudinal axis; an outboard driving sprocket rotatably mounted on said framework about a second common longitudinal axis parallel to said first axis and located below said conveyor means;

an endless conveyor chain enmeshed about the inboard and outboard sprockets to thereby form a continuous loop, the top surface of said chain on said sprockets being below the upper surface of said receiving table and the total length of said chain being greater than the minimum loop necessary to encircle the two sprockets;

a supporting structure mounted on said framework intermediate said inboard and outboard sprockets in transverse alignment therewith, including a horizontal plate on which said chain is supported;

linkage means connecting said supporting structure to said framework adapted to move said supporting structure from a first location wherein the top surface of said chain is elevated below the upper surface of said receiving table and a second location wherein the top surface of said chain is elevated above the upper surface of said receiving table.

4. A device for separating vertically stacked boards, comprising:

a fixed supporting framework;

- a delivery conveyor mounted on said framework adapted to convey vertically stacked boards;
- a horizontal receiving table located on said framework adjacent the delivery end of said conveyor having an

- upper surface adapted to support the stacked boards deposited thereon by said conveyor;
- a plurality of lateral chain conveyors mounted on said framework across the lengths of stacked boards deposited on said table, each of said conveyors including a pair of sprockets mounted on said framework for rotation about laterally spaced parallel longitudinal axes, a chain loosely enmeshed about said pair of sprockets in a closed loop, and a vertically movable supporting frame mounted below the upper 10 chain flight in supporting engagement therewith, said supporting frame being movable between a first position wherein the top surface of the chain supported thereon is located below the upper surface of said receiving table and a second position wherein the top surface of the chain supported thereon is located above the upper surface of said receiving table;
- a fixed abutment mounted on one framework adjacent said aligned sprocket of each of said chain conveyors, said abutment extending the length of said receiving 20 table and being located parallel to the position of the stacked boards deposited thereon, the top edge of said abutment being located above the top surfaces of said lateral conveyor chains when in said second position at a height less than the thickness of the 25 lower board to be separated;
- common drive means connected to said lateral conveyors adapted to propel vertically stacked boards supported on said lateral conveyors against said abutment with force sufficient to cause boards resting on the lowermost board of each stack to slide therefrom over said abutment;
- and a longitudinally directed roller conveyor mounted on said framework with the rollers thereof interspersed between said lateral conveyors in parallel 30 relation thereto, the elevation of the top tangential horizontal surfaces of said rollers being intermediate the elevations of the top chain surfaces of said lateral conveyors at said first and second positions.
5. A device as defined in claim 4 wherein the supporting surface of said delivery conveyor is elevated above 40 said upper surface of said receiving table;
- a hinged plate pivotally mounted on said receiving table about a horizontal axis adjacent the delivery end of 45 said delivery conveyor and at an elevation equal to

5

15

20

30

35

40

45

- that of said receiving table, said plate being in the path of boards deposited on said receiving table by said delivery conveyor;
- means urging the edge of said plate opposite to its pivot axis to an elevation above that of its pivot axis;
- and control means operatively connecting said plate and said supporting frame of each lateral conveyor adapted to raise said frames from their first position to their second position responsive to downward motion of said opposite edge of said plate.
6. The device as defined in claim 4 further comprising: a receiving conveyor on said framework spaced outwardly of said abutment;
- a movable gate pivotally mounted on said framework adapted to occupy a first position wherein it bridges the space separating said abutment and said receiving conveyor and being adapted to be pivoted relative to said framework to a second position thereby opening the space separating said abutment and said receiving table;
- actuating means on said framework connected to said gate adapted to selectively pivot said gate from said first position to said second position;
- and manually operable control means operatively connected to said actuating means.
7. The device as defined in claim 4 further comprising: movable arms pivotally mounted on said framework adjacent said abutment for motion about horizontal transverse axes from a first position wherein said arms are entirely below the elevation of the top edge of said abutment to a second position wherein said arms project upwardly above the top edge of said abutment;
- actuating means on said framework operatively connected to said arms adapted to selectively move said arms from said first position to said second position;
- and manually operable control means operatively connected to said actuating means.
